UNITED STATES PATENT OFFICE.

EDUARD BRESLAUER, OF LEIPSIC, GERMANY.

NOTE-DISK HOLDER FOR MECHANICAL MUSICAL INSTRUMENTS.

SPECIFICATION forming part of Letters Patent No. 623,878, dated April 25, 1899.

Application filed January 7, 1899. Serial No. 701,476. (No model.)

To all whom it may concern:

Be it known that I, EDUARD BRESLAUER, a subject of the King of Prussia, Emperor of Germany, residing at Leipsic, in the Kingdom 5 of Saxony, Germany, have invented certain new and useful Improvements in Note-Disk Holders for Mechanical Music Instruments, of which the following is a specification.

My invention refers to improvements in 10 note-disk holders for mechanical music instruments, its object being to simplify the insertion of the note-disks. For this purpose I provide for each note-disk a separate holder having swiveled thereto a note-disk carrier to 15 be rotated by the driving-shaft and to which the note-disk is attached in the usual manner. A suitable number of such holders, with carriers and note-disks, are loosely mounted on a shaft traversing the casing, arranged in such 20 a manner that any one of them can be brought opposite the end of the driving-shaft and moved up to the latter to bring the driving-shaft into engagement with the disk-carrier, the disk then being in the proper position to 25 operate the reeds.

The nature of my invention will be best understood when described in connection with the accompanying drawings, in which—

Figure 1 represents a front view of a music- 30 box embodying my invention, the casing being in section. Fig. 2 is a side elevation of Fig. 1. Fig. 3 is a transverse section on the line 3 3, Fig. 1. Fig. 4 is a detail view of the disk-holder, carrier, and disk. Figs. 5 and 6 35 are front elevation and sectional plan of a modification.

Similar letters of reference designate corresponding parts throughout the several views of the drawings.

40 In the figures the letter M designates the casing; N, the motor; n, the driving-shaft actuated by the motor, and R the reeds.

A is a shaft traversing the casing and removably secured thereto or so arranged that 45 one end may be made accessible for placing thereon a series of note-disk holders with the disks mounted thereon or for removing the same.

T' T², &c., are note-disk holders provided 50 with suitable disk-carriers a, swiveled thereto and adapted to be engaged by the driving-shaft n and rotated thereby. The holders T'

T², &c., are formed to be mounted on the shaft A so as to be easily rotated on this shaft and also to be moved in axial direction. The 55 holders have arms projecting through the casing and provided with handles G' G², &c., and with balance-weights C' C². When not in action, the holders are in such a position that the note-disks clear the driving-shaft n, 60 so that they may be shifted in axial direction on the shaft A, as the holder T' in Fig. 1. The box should be wide enough to admit the whole number of disk-holders to be shifted on the shaft A either to the right or to the left of the 65 end of the shaft n, so that any one of the holders may be shifted in front of the shaft n and then pushed up to it to bring the driving-shaft n into engagement with the disk-carrier.

70 The box containing the apparatus may be formed in any desirable manner, means being provided for inserting the disk-holders, with the disks attached thereto, through a suitable door and to make the ends of the 75 handles accessible from the outside.

In the example shown I have provided slots S', S², and S³ in the end of the casing, through which the outer arms of the holders project, are moved across the box in the slot S', de- 80 pressed in the slot S², and finally shifted in the slot S³, so as to move the note-disk carrier into engagement with the shaft n and the note-disk up to the reeds.

W W are partitions to protect the inside of 85 the casing against dust. Of course a removable cover may also be placed over the handles.

To properly register the note-disk, any suitable friction-slide on the holders may be used, 90 the slide normally engaging the notch in the note-disk and being withdrawn as the disk-carrier is brought over the shaft n.

Each one of the handles G' G², &c., is by 95 preference provided with a tag or inscription designating the piece of music, so that any one of the pieces on the shaft A may be selected, as desired.

Figs. 5 and 6 show a modification in which the note-disks are driven by a pin-wheel en- 100 gaging holes near the outer edges of the note-disks.

What I claim as new is—

1. In a music-box, the combination of a

shaft A secured within the music-box in the manner described; a series of note-disk holders with projecting handles, loosely pivoted on said shaft A; a driving-shaft n , which is cleared by the note-holders not in action, but with which any single note-disk is brought into engagement by turning its inner end up and pushing it up to the shaft n , and reeds R, actuated by the note-disks, substantially as described.

2. In a music-box, the combination of a shaft A secured within the music-box in the manner described; a series of note-disk holders with projecting handles having inscriptions designating the particular piece of music, the handles being loosely pivoted on said shaft A; a driving-shaft n , which is cleared by the note-holders not in action, but with which any single note-disk is brought into engagement by turning its inner end up and pushing it up to the shaft n , and reeds R, ac-

tuated by the note-disks, substantially as described.

3. In a music-box, the combination of a shaft A secured within the box in the manner described; a series of note-disk holders T', T², &c., with projecting handles G' G²; said handles being loosely mounted on the shaft A; a driving-shaft n , which is cleared by the holders not in action, but with which any single note-disk is brought into engagement by depressing the handle of the holder and shifting it against the shaft n , and slots S', S² and S³ in the casing, substantially as and for the purpose specified. 35

In testimony whereof I have hereunto set my hand in the presence of two subscribing witnesses.

EDUARD BRESLAUER.
